(57) **CLAIM**

I claim, the ornamental design for electronic device, as shown and described.

DESCRIPTION

FIG. 1 is a front perspective view of electronic device, showing my new design;

FIG. 2 is a front view thereof;

FIG. 3 is a rear view thereof;

FIG. 4 is a side view thereof;

FIG. 5 is another side view thereof;

FIG. 6 is a top plan view thereof; and,

FIG. 7 is a bottom plan view thereof.

The broken line features of the electronic device form no part of the claim.
